S. F. ARBUCKLE,
TWO-WAY TILTING REFLECTOR FOR LAMPS,
APPLICATION FILED SEPT. 20, 1919.

1,398,292.

Patented Nov. 29, 1921.

UNITED STATES PATENT OFFICE.

SAMUEL F. ARBUCKLE, OF INDIANAPOLIS, INDIANA, ASSIGNOR TO UNITED STATES AUTOMOTIVE CORPORATION, OF CONNELLSVILLE, INDIANA, A CORPORATION OF DELAWARE.

TWO-WAY-TILTING REFLECTOR FOR LAMPS.

1,398,292.

Specification of Letters Patent. Patented Nov. 29, 1921.

Application filed September 20, 1919. Serial No. 325,230.

To all whom it may concern:

Be it known that I, SAMUEL F. ARBUCKLE, a citizen of the United States, and a resident of Indianapolis, county of Marion, and State 5 of Indiana, have invented a certain new and useful Two-Way-Tilting Reflector for Lamps; and I do hereby declare that the following is a full, clear, and exact description thereof, reference being had to the accompanying drawings, in which like numerals refer to like parts.

This invention relates to a two way tilting reflector headlight or lamp, and especially those types of lamps used upon motor vehicles, motor boats and the like. The construction herein shown has in it some features in common with that shown in Letters Patent No. 1,376,191, patented April 26, 1921, in the name of Charles L. De Martin, 15 William M. Matteoli and Samuel F. Ar- buckle, which application was copending with this application.

The main object of this invention is to provide a lamp or headlight which will project the light or glare therefrom straight ahead, downwardly or to the side, as desired, and more particularly to the mounting 25 of a tilting reflector which may be controlled and tilted vertically or laterally at the will 30 of the operator in positive manner.

Another feature of the invention is the construction of a double action tilting reflector headlight, whereby it may be constructed and assembled in the most convenient and practical manner so that the 35 various working parts are formed and held together so as to be readily demountable from the casing thereof. By means of this construction the reflector and all attached 40 parts thereof for tiltably mounting it and actuating it are formed in a single unit to permit its ready mounting or dismounting from the casing.

In the drawings, which are made a part 45 of this application, Figure 1 is a vertical cross section through a lamp showing the tilted reflector mounted in the casing in position to project the rays of light forwardly and parallel. Fig. 2 is the same as 50 Fig. 1 showing the reflector in tilted position for projecting the rays of light forwardly and downwardly. Fig. 3 is a top plan view looking down upon the reflector with the upper portion of the casing re- 55 moved, the reflector being in position to

project the rays of light forwardly, either parallel or downwardly. Fig. 4 is the same as Fig. 3 showing the reflector in position to project the rays of light laterally, either parallel or downwardly. Fig. 5 is a section 60 taken on the line 5—5 of Fig. 1. Fig. 6 is a section taken on the line 6—6 of Fig. 5.

In the drawings there is shown a lamp casing 10 parabolic in form having a door rim 11 mounted thereon in which is secured 65 a lens 12 in any suitable manner. The casing 10 is provided with an outwardly extending peripheral flange 13 adapted to telescope within the rim 14 which is provided with a forward portion having a depression 70 therein, in which a cord 15 is mounted for sealing the space between the lens 12 and said rim, and a rearwardly extending upper flange portion in which the peripheral flange 13 engages, whereby said rim 14 is securely 75 fixed within the casing 10. Mounted upon said rim there are spring hinge members 16 so positioned as to be in the vertical axis therethrough and provided with holes in their inner portion into which the pins 17 80 extend for pivotally hinging and securing the ring 18 therein, whereby said ring 18 is pivotally mounted so as to swing laterally within the rim 14. The inner surfaces of the rim 14 and the ring 18 are nickelized so as 85 to provide a reflecting surface in continuation of the reflector 19. The ring 18 is provided with a bow 20 consisting of a metal strip fixedly secured to the periphery of said ring in the line of the vertical axis extending 90 therethrough, and extending around and spaced apart and rearwardly from the rear of the parabolic reflector 19 so as to inclose said reflector in a plane through its vertical axis. The reflector 19 is hinged at its bot- 95 tom within the ring 18 by means of the spring hinges 21 shown in Figs. 5 and 6 to permit the reflector to tilt forwardly and vertically within the ring 18, as shown in Figs. 1 and 2. A plate spring 22 is mounted 100 upon the bow 20 so as to engage a projection 23 on the upper rear portion of the reflector 19 so that said reflector is normally forced downwardly into tilting position, as shown in Fig. 2 under a constant spring tension. 105 For overcoming said spring tension and returning the reflector to and maintaining it in its vertical position, as shown in Fig. 1, there is provided a fluid actuating means 24 consisting of a metal bellows which contracts 110

2
and pulls the reflector back into position by the suction produced from the intake manifold of an internal combustion engine, not shown herein, upon the release of said suction, the spring 22 causing said reflector to be tilted forwardly, as shown in Fig. 2. The construction and operating mechanism above described in which the mounting of the reflector and its operation is such that it may 10 be controlled so as to project the light parallel and forwardly, or downwardly and forwardly, as desired.

Mounted upon the outer periphery of the rim 14, and extending around the rear side 15 of the reflector there is a strip 25 bent so as to form a seat 26, and provided with a longitudinal slot therein through which a pin 27 mounted on the bow 20 extends so as to hold said strip in position and permit 20 lateral swinging movement of the reflector, ring 18, and bow 20 upon the hinge pins 17, which movement will permit the reflector to project the rays of light forwardly or laterally. For actuating the reflector and 25 causing it to swing to the position shown in Fig. 4 for projecting the rays of light laterally, there is a metal bellows 28 secured upon the seat 26 and connected to the bow 20 so that when it is contracted by 30 the vacuum it will pull said bow laterally, and said bow being fixedly secured to the ring 18 in which the reflector is mounted will cause said reflector to swing on the pivot pins, as shown. Said bellows is connected 35 up with the intake manifold of the motor or any other suitable means not shown herein. The reflector is returned to its normal position in which the rays of light are forwardly projected, as shown in Fig. 3 by 40 means of a spring 29 connecting the end of the strip 25 with the bow 20.

In operation, if the driver of a vehicle desires to have his light projected at a distance ahead of him, he opens a valve which 45 causes the bellows 24 to contract and hold the reflector in the position shown in Fig. 1, if he wishes the light projected forwardly and downwardly, he tilts his reflector by closing the valve, releasing the vacuum in the 50 bellows 24 and permitting the spring 22 to tilt the reflector forward, if it is desired to swing the rays of light laterally and at a distance ahead, he operates both the bellows 28 and 24 in a like manner so as to 55 cause the reflector to swing in the position shown in Fig. 4 and remain in the vertical

position shown in Fig. 1; and if it is desired to throw the light laterally and downwardly, he releases the bellows 24 so that the reflector will take the position shown 60 in Fig. 2 and operate the bellows 28 so that it will take the position shown in Fig. 4.

The invention claimed is:

1. A lamp having a movable reflector therein, a member removably mounted in 65 said lamp in which said reflector is pivotally mounted for permitting the vertical tilting thereof, a second member in which said first mentioned member is pivotally mounted for permitting the lateral turning of said 70 member and reflector therein, an actuating means mounted between said first member and reflector for tilting the latter, and a second independently mounted actuating means connecting said second mentioned 75 member with said first member for controlling the movement within said first member.

2. A lamp having a movable reflector therein, a frame upon which said reflector is pivotally mounted, a second frame removably mounted in said lamp on which said first mentioned frame is pivotally mounted, actuating means mounted within said first mentioned frame for adjusting the position of the reflector therein, and a second 80 actuating means mounted within said second mentioned frame for adjusting the position of said frame within said first mentioned frame, whereby the rays of light projected 85 therefrom may be independently directed 90 downwardly or laterally.

3. In combination with a lamp having a casing and a source of light therefor, of a single unit adapted to be detachably mounted within said casing, including a 95 fixed rim, a movable ring pivotally mounted within said rim, a reflector pivotally mounted within said ring, a bow secured on said ring and extending around said reflector, actuating means connecting said reflector and bow for controlling the movement of said reflector in one direction, a support on said fixed rim, and an actuating means connecting said support and bow for controlling movement of said movable ring 100 for moving the reflector in another direction, whereby the rays of light projected therefrom may be independently directed downwardly or laterally.

In witness whereof, I have hereunto af- 110 fixed my signature.

SAMUEL F. ARBUCKLE.
